UNITED STATES PATENT OFFICE.

J. WALTER SPALDING, OF NEW YORK, N. Y., ASSIGNOR TO A. G. SPALDING & BROTHERS, OF CHICAGO, ILLINOIS.

DESIGN FOR THE ORNAMENTATION OF GAME-TABLETS.

SPECIFICATION forming part of Design No. 18,470, dated July 17, 1888.

Application filed January 12, 1888. Serial No. 260,579. Term of patent 7 years.

To all whom it may concern:

Be it known that I, J. WALTER SPALDING, a citizen of the United States, and a resident of the city, county, and State of New York, 5 have invented and produced a new and original Design for the Surface Ornamentation of Game-Tablets, of which the following is a specification, reference being had to the accompanying drawing, forming part thereof.

- 10 The design hereinafter set forth is particularly adapted to the surface ornamentation of game-tablets of any suitable forms or materials, and in the accompanying illustration is illustrated in connection with a circular tablet.
- 15 The design as thus embodied has for its particular characteristic or leading feature a representation in connection with the game of lawn-tennis. As therein delineated, it consists of the head and portion of the bust of a 20 female figure, the shoulders being covered with drapery and having a hat upon her head.

A racket and ball are also represented. As shown, the racket is behind the head of the figure, only a portion of the handle being shown, and the ball is upon the racket, the 25 latter forming also a suitable background to the figure. The whole may be inclosed by a suitable border or not, as fancy may dictate.

What I claim is—

The design for the surface ornamentation of 30 game tablets, the same consisting of the representation of the head and bust of a female figure with the grid of a tennis-racket as a background, having a ball on said grid, substantially as shown and described. 35

In testimony whereof I have signed my name to this specification in the presence of two subscribing witnesses.

J. WALTER SPALDING.

Witnesses:

W. T. SIMPSON,
J. N. CURTISS.
